UNITED STATES PATENT OFFICE

2,585,136

COLD AIR RETAINING DEVICE FOR
REFRIGERATORS

George T. Kuchler, Brooklyn, N. Y.

Application August 14, 1948, Serial No. 44,316

1 Claim. (Cl. 160—37)

1

This invention relates, in general, to refrigerators, and more particularly to devices for retaining the air of low temperature of a refrigerator within the same, to prevent it from being discharged to any great extent, on the opening of the refrigerator.

Heretofore, attempts have been made to retain the cold air when the door was open, by the provision of closed food containers supported within the case, but the cold air surrounding the containers was to a large extent sucked out by the opening of the door, and would descend at the outside of the case, often chilling the user.

This invention contemplates retaining the entire cold air of a refrigerator case within the same by a movable barrier interposed between the shelving and the door, so that on the opening of the door the cold air is retained within the compartments and not sucked or drawn out by the door. The barrier is preferably in the form of a blind which is transparent so that the user can determine the location of the article sought to be removed from the refrigerator, and then move the blind to enable the article to be grasped, and thereafter return the blind to closing position before the cold air can start its movement to the outside of the case. As most of the articles in more frequent use can be arranged on the upper shelves, a main body of cold air is always maintained at the lower levels, enclosed by the blind, even though the blind exposes the upper levels. When desired, the entire front of the case may be opened by the movement of the blind or barrier, which is then placed in a position within the case so as not to impede access to the front opening of the case.

The invention consists of a blind or barrier, preferably of transparent plastic material, which is placed to close the front opening of the case, so that when the door is open, said barrier takes the place of the door in so far as preventing the emission of the cold air of the case, and which barrier is movable to permit access to any part of the interior of the case, by its movement, and if not desired to perform the function of a barrier, it may be concealed within the case.

The invention will be more fully described hereinafter, embodiments thereof shown in the drawings, and the invention will be finally pointed out in the claim.

In the accompanying drawings,

Fig. 1 is a perspective view of a known refrigerator case having my invention embodied therein;

Fig. 2 is a diagrammatic section, on line 2—2 55 The side walls 24 of the case, are provided with

2

of Fig. 1, but with the blind or barrier in its uppermost position;

Fig. 3 is a partial view with the blind or barrier in inactive position;

Fig. 4 is a section on line 4—4 of Fig. 3;

Fig. 5 is a front partial view of the blind or curtain;

Fig. 6 is a side view of one of the tracks or channel guidings;

Fig. 7 is a front view of the top of the blind;

Fig. 8 is a section on line 8—8 of Fig. 7;

Fig. 9 is a section on line 9—9 of Fig. 7;

Fig. 10 is a sectional view of the top fastening device taken on the line 10—10 of Fig. 7;

Fig. 11 is a front view of the lower end of the blind, and

Fig. 12 is a section taken on line 12—12 of Fig. 11.

Similar characters of reference indicate corresponding parts throughout the various views.

Referring to the drawings, and more particularly to Figs. 1 to 3, a known type of refrigerator case 10 is shown, to which my invention has been applied.

25 The cold air retaining blind 15 closes the otherwise open fronts of the compartments 16 formed by the shelves 17; by having the upper end 20 of the blind 15 abut against the uppermost partition 21, and having its lower end 22 extend below false bottom 23 forming a bottom of a container in the refrigerator, as shown in Fig. 2.

The blind 15, in the embodiment shown, extends the entire width of the refrigerator case, as shown in Fig. 1, where the blind is shown as only partially extended, in order to leave the two upper compartments open.

When it is desired to have all of the compartments open, the blind 15 is in the position as shown in Fig. 3, with the end 20, at the false bottom 23, and the end 22 extended upwardly at the rear of the case 10 behind certain of the shelves 17 forming the compartments 16. The height of the end 22 when withdrawn is determined by the length of the blind 15, after covering the bottom of the case, and with the end 20, about at the false bottom 23 (Fig. 3). The false bottom 23 may be formed by the bottom of a pan 18, having its bottom held above the bottom of the case.

40 Thus, the blind 15 may be raised to its entire closing position, as shown in Fig. 2, or lowered to its entire open position, as shown in Fig. 3, or may have any intermediate position, as shown, for example, in Fig. 1.

45 50 The side walls 24 of the case, are provided with

U shaped tracks 25 held thereto by screws 26 (Fig. 4). These tracks act as guideways for the blind and extend downwardly and along the bottom of the case. Preferably, they extend upwardly from the bottom along the sidewalls of the case at the front thereof (Fig. 1). The track 25 is shown in Fig. 6, and has an opening 27 at its upper end, and two curved portions 28 and 29. A section 25a of the track may be removed, and the blind taken out for cleaning, and easily replaced.

Preferably the strips of the blind are of transparent plastic to enable the consumer to see the contents of the box when the blind is entirely closed.

The embodiment of a blind 15 is shown in Figures 5, 7, 11 and 12.

A plurality of strips 30 of suitable plastic, are arranged adjacent each other at their lateral edges. At the end 22, one of the corners is rounded as at 31 (Fig. 12), to enable the end to move freely when it passes through the curved portions 28 and 29 of the track 25.

Each of the strips 30 has openings or bores 33 transversely across it for the passage of cords 34. One end of each of these cords is knotted as at 36, and abuts against a flange end 37 of a sleeve 38 around which a spring 39 is arranged which has an expansive effect between the flange 37 and the edge of the strip 30, whereby all of the strips are held contiguous to each other. This pressure device is arranged preferably at the innermost end of the blind, that is, at its lower end 22.

The other end 20, has a handle 40 at the front thereof. This is preferably of the spring type to enable a clamping of the end 20 to the sides of the case.

A rod 41 having an end 42, to enter the opening 27 in the side walls of the case, has a short plate 44 held thereto by screws 45 (Fig. 10). A spring 46 presses against the plate. The other end of the spring presses against a similar plate fixed to a similar rod. The plates act as a pair of handles and preferably, an additional plate 47 is provided to act as a handle (Fig. 9). Bringing the plates toward each other, extracts the ends from the openings, and permits the blind to be lowered. A plurality of openings may be provided in the tracks, or the pressure of the spring may be relieved on. The strips remain in their faying relationship, during the movement of the rod or crossbar 41 longitudinally in the tracks.

A shell 48 surrounds the rods 41, and this shell is held to the uppermost strip 30 by a metallic strap member 49 (Figs. 8 and 9). The uppermost strip has a cut out 50 into which the knotted end 51 of the cord 34 fits (Fig. 7). Thus the cord and strap member provide securing means.

An embodiment of the invention has been described, and the invention enables much of the cold air to be held in the refrigerator instead of being disseminated when a door is opened, without it doing useful work.

The benefit to the consumer is that he can open 65 the outer door without losing hardly any of the established temperature; and he can see what he

needs. Then if the article is on the first or second shelf he need only lower the blind to that point, thereby saving the temperature on the shelves and the space below. Thus he stops the warm air from replacing the cold air that would ordinarily be sliding out at the bottom. The warm air would also raise the temperature, to say the least. This saving of temperature would not let the thermostat start the motor as often. So there would be 10 also as a result a considerable saving in the power bill each month. Needless to say, the wear and tear on the motor and other moving parts could more than be easily observed, the maintenance bills or charges would drop in proportion also.

15 I wish it to be understood that I do not desire to be limited to the exact details of construction shown and described, for obvious modifications will occur to a person skilled in the art.

I claim:

20 In a refrigerator having a case with a front opening, the combination with tracks arranged along the sides of the case at the interior thereof extending the full height of said front opening along both sides of the case, and within the case 25 the length of said height, of a cross bar transversely across the front opening and having its outer ends guided in said tracks, means holding said cross bar in an adjusted position in said tracks, a plurality of cords, each having one end 30 secured to said cross bar, an abutment on the other end of each cord, the length of each cord being substantially equal to the height of the front opening, a plurality of helical springs each surrounding one of said cords and each having 35 one end held on the cord against said abutments, the other end of the spring being free to move, a plurality of strips each extending across the front opening parallel with said cross bar, their ends enclosed by the tracks, and having openings 40 for the passage of said cords, said strips being disposed in edge to edge contact from said cross bar to the free ends of said springs in pressed faying relationship, whereby said strips are adapted to be moved in close fitting relationship, 45 as a unit from a complete closure position of the front opening to a concealed position in the case with the front opening entirely open, and to any intermediate position.

GEORGE T. KUCHLER.
